LAWN SPRINKLER

John D. Beinert, Babylon, N.Y., assignor to International Patent Research Corp., New York, N.Y., a corporation of New York

Filed Nov. 19, 1963, Ser. No. 77,485

Term of patent 7 years

(Cl. D91—1)

FIG. 1 is a perspective view of a lawn sprinkler showing my new design, it being understood that the grid-like texture on the rear panel extends throughout the designated area, as shown by FIG. 4.

FIG. 2 is a fragmentary side elevational view thereof on an enlarged scale;

FIG. 3 is a fragmentary top plan view thereof;

FIG. 4 is a rear elevational view thereof;

FIG. 5 is a front elevational view thereof, with the sprinkler arm and actuating elements omitted for the convenience of illustration;

FIG. 6 is an enlarged fragmentary cross sectional view taken along the line 6—6 of FIG. 4.

The essential features of my design reside in those features shown in full lines.

I claim:

The ornamental design for a lawn sprinkler, as shown and described.
